COMBINED DISHWASHER AND FAUCET FIXTURE

Fred W. Hall, Toledo, Ohio, assignor to Gerity Products,
Inc., Toledo, Ohio, a corporation of Michigan

Filed Oct. 31, 1963, Ser. No. 77,223

Term of patent 14 years

(Cl. D91—3)

Fig. 2

Fig. 3

Fig. 4

FIGURE 1 is a perspective view of a combined dishwasher and faucet fixture, showing my new design;
FIGURE 2 is a front elevational view thereof;

FIGURE 3 is a side elevational view thereof; and
FIGURE 4 is a top plan view thereof.

I claim:

The ornamental design for a combined dishwasher and faucet fixture, substantially as shown.
